[57] CLAIM

The ornamental design for a warm air diverter for earth moving machine, as shown and described.

DESCRIPTION

FIG. 1 is a front elevational view of a warm air diverter for earth moving machine, showing my new design;

FIG. 2 is a side elevational view thereof;

FIG. 3 is a side elevational view thereof, of the opposite side of FIG. 2;

FIG. 4 is a rear elevational view thereof;

FIG. 5 is a front perspective view thereof;

FIG. 6 is a rear perspective thereof; and

FIG. 7 is a front perspective view thereof, the earth moving machine is partially shown in broken lines for illustrative purposes only and forms no part of the claimed design.

FIG. 1

FIG. 2

FIG. 3

FIG. 4

FIG. 5

FIG. 6

FIG. 7
